Herbert D. La Mont, Huntington, Ind.

Application June 28, 1946, Serial No. 131,152

Term of patent 7 years

(Cl. D44—1)

To all whom it may concern:

Be it known that I, Herbert D. La Mont, a citizen of the United States, residing at Huntington, in the county of Huntington and State of Indiana, have invented a new, original, and ornamental Design for a Dutch Oven or the like, of which the following is a specification, reference being had to the accompanying drawing, forming part thereof.

I claim:

The ornamental design for a Dutch oven or the like, as shown.

HERBERT D. LA MONT.
